UNITED STATES PATENT OFFICE.

WILLIAM THOMAS DONNELLY, OF BROOKLYN, NEW YORK.

FLOATING DRY-DOCK.

No. 920,286.

Specification of Letters Patent.

Patented May 4, 1909.

Application filed August 18, 1908. Serial No. 449,120.

To all whom it may concern:

Be it known that I, WILLIAM THOMAS DONNELLY, a citizen of the United States, residing at Brooklyn, in the county of Kings 5 and State of New York, have invented certain new and useful Improvements in Floating Dry-Docks, of which the following is a specification.

My invention relates to an apparatus and 10 method for controlling the raising and lowering of floating dry docks.

My invention relates particularly to a manner of simplifying the construction and operation of large floating dry docks, and 15 deals with a method of so arranging the flood-gates and pumping machinery, that in operation, the manipulation or control of the dock and vessel is precisely similar in raising and lowering. To accomplish this, I divide 20 the dock into a number of separate water-tight compartments and provide for each, a single valve or gate, which controls both the in-flow and out-flow of water and further enables the control of the rise of the dock to be 25 independent of the operation of the pumping machinery.

It will be understood that in the larger size of docks, upward of 100 feet wide and several hundred feet in length, it becomes 30 difficult to quickly and positively control a complicated system of machinery and gates, involving the safety of dock and vessel; hence, the importance of simplicity in construction and operation.

Heretofore, an entirely different system of control has applied to the raising and lowering of floating dry docks, but with the apparatus and method herein described, the control of the lowering and raising of the 35 dock is precisely similar, and any skill or facility acquired is equally applicable to both operations.

In the drawings: Figure 1, is a plan view of a floating dry dock having my invention applied. Fig. 2, a side view thereof. Fig. 3, a transverse vertical sectional view, on an enlarged scale and partly in section, of one of the pontoons having my invention applied.

Like reference characters designate corresponding parts in the figures of the drawings illustrating my invention.

Referring to the drawings, 1. represents the floating dry dock which, as shown in the accompanying drawings, comprises four hollow pontoons 2, but the number thereof may be varied according to requirements. These

pontoons are connected at their ends by walls or wings 3, mounted upon their decks and secured thereto in any suitable manner.

The usual centrally located keel-blocks 4 and laterally located bilge-blocks 5 are provided upon the decks of the pontoons, and interiorly each pontoon is divided by a transverse water-tight bulkhead 6 into two compartments 7 and 8.

A combined inlet and outlet opening 9 is provided in each end wall of each pontoon, and said openings are opened and closed by gates or valves 10 raised and lowered by means of vertical rods 11 mounted in brackets 12 on the sides and pontoons, the lower ends of said rods being secured to said valves and the upper ends being screw-threaded and provided with hand wheels 13 by which they are operated. A centrifugal 75 pump 14 of any suitable size and design is mounted in each water-tight compartment of the pontoons, the openings 15 into the bodies 16 of the casings thereof being secured in registry with the openings 9 in the 80 end walls of the pontoons and serving as combined outlets and inlets for the pumps to and from the exterior of the pontoons and the openings 17 into the branches or feet 18 of the casings, serving as combined outlets 85 and inlets for the pumps to and from the interior of the pontoons, from which construction and arrangement it will be apparent that water can be readily admitted to and discharged from each compartment of the 90 pontoons through its individual pump, which constitutes a combined inlet and outlet therefor, thus obviating the necessity for an extra gate in each compartment of the 95 pontoons to flood it.

The wheels of the pumps are secured on the lower ends of vertical shafts 19, journaled in bearings 20 on the pontoons and wings, and having bevel gears 21 on their upper ends meshing with bevel gears 22 on the horizontal shafts 23, journaled in bearings 24 on the tops of the wings, and driven by any suitable power, such, for instance, as electricity or compressed air, thereby affording means for driving all the pumps on each 105 side together.

It will be understood that the smaller the openings to the pontoons the smaller the amount of water allowed to enter or depart therefrom and the longer the time required 110 to raise or lower the dock, and that the larger the openings to the pontoons the

larger the amount of water allowed to enter or depart therefrom and the shorter the time required to raise or lower the dock, therefore, it will be understood that by adjusting the gates so as to give the size of opening required, the dock can be raised or lowered level and the time for raising and lowering it governed.

I will now describe the operation of my floating dry dock in handling a vessel, it being assumed that the dock is raised and ready for sinking, with the keel and bilge blocks prepared to receive the vessel and the pumps stopped.

15 The valves or gates on both sides of the dock are primarily raised or opened to the same degree allowing water to flow into each compartment of the pontoons, through its individual pump, in equal amounts, causing 20 the dock to sink, and if the dock does not sink level or at the speed desired, the valves or gates are adjusted on the low side to closed or partially closed position until it levels up. When the dock has been lowered 25 to the required depth, the valves or gates are then lowered or closed, the vessel centered in the dock, the pumps started and the valves or gates thereafter primarily opened to the same degree, whereupon the water 30 will be discharged from each compartment of the pontoons, through its individual pump, in equal amounts, causing the dock to rise, and if it does not rise level or at the speed desired, the valves or gates are ad- 35 justed on the high side to a closed or partially closed position until it levels up. When the dock has raised so as to bring the hull of the ship out of the water, the gates or valves are closed.

40 My method, which is conveniently carried out by means of the above described apparatus, consists essentially in establishing a separate flow of water, by means of the gates, from the exterior of a floating dry dock into 45 each water-tight compartment thereof, through the combined inlets and outlets, formed by the individual pumps, interrupting the in-flow of water, by means of the gates, to sustain the dock in its lowered position, then producing a static condition of 50 out-flow of water in said compartments, by means of the pumps, thereafter establishing a separate reverse flow of water, by means of the gates, from each water-tight compartment through the combined inlets and outlets, formed by the pumps, and finally interrupting the flow of water, by means of the

gates, to sustain the dock in its raised position.

I do not wish to be understood as limiting myself to the details of construction and arrangement as herein described and illustrated as it is manifest that variations and modifications may be made in the features of construction and arrangement, in the adaptation of the device to various conditions of use, without departing from the spirit and scope of my invention and improvements. I, therefore reserve the right to all such variations and modifications as properly fall within the scope of my invention and the terms of the following claims.

What I claim is:

1. In a floating dry-dock having separate water compartments, a centrifugal pump in each of said water compartments for the admission and exhaust of water to and from said compartments power connections for each pump extending from the upper portion of the dock, each of said pumps establishing communication only with the compartment in which it is located and the exterior of the dock and having a combined inlet and outlet to the exterior of the dock, a combined inlet to and outlet from the compartment in which it is located and a single valve for each of said pumps for controlling the passage of water therethrough, substantially as described.

2. In a floating dry-dock having pontoons provided with separate water compartments, a centrifugal pump in each of said water compartments for the admission and exhaust of water to and from said compartments power connections for each pump extending from the upper portion of the dock, each of said pumps establishing communication only with the compartment in which it is located and the exterior of the pontoon, and having a combined inlet from and outlet to the exterior of the pontoon, a combined inlet to and outlet from the compartment in which it is located and a single valve for each of said pumps for controlling the passage of water therethrough, substantially as de- 105 scribed.

In testimony whereof I have signed my name in the presence of two subscribing witnesses.

WILLIAM THOMAS DONNELLY.
